CLAIM

I claim the ornamental design of a kneeling platform, as shown and described.

DESCRIPTION

FIG. 1 is a top plan view of the kneeling platform showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a sectional view taken along line 7-7 of FIG. 1; and,

FIG. 8 is a sectional view taken along line 8-8 of FIG. 1.
